[57] CLAIM

The ornamental design for a refrigerator, substantially as shown and described.

DESCRIPTION

FIG. 1 is a front elevational view of the refrigerator showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and

FIG. 7 is a cross-sectional view of the refrigerator, taken along line 7—7 of FIG. 3.

The broken lines in the drawings forming a door handle and a refrigeration coil are for illustrative purposes only and form no part of the claimed design.

FIG. 1

FIG. 2

FIG. 3

FIG. 4

FIG. 5

FIG. 6
